(57) **CLAIM**

The ornamental design for a folding memo board, as shown and described.

DESCRIPTION

FIG. 1 is a front elevational view of a folding memo board of the present invention showing my new design, shown in a folded condition with a locking tab in a locked condition; FIG. 2 is a rear elevational view of the folding memo board of FIG. 1;

FIG. 3 is a left end elevational view of the folding memo board of FIG. 1, the right end elevational view being a mirror image thereof;

FIG. 4 is a top plan view of the folding memo board of FIG. 1;

FIG. 5 is a bottom plan view of the folding memo board of FIG. 1;

FIG. 6 is a front elevational view of the folding memo board of FIG. 1, but shown in an open condition;

FIG. 7 is a rear elevational view of the folding memo board of FIG. 6; and,

FIG. 8 is a left end elevational view of the folding memo board of FIG. 6, the right end elevational view being a mirror image thereof.

Broken lines appearing in the Figures are for illustrative purposes only. They are intended to disclose the environment related to the claimed design and to define the bounds of the claim, but are not intended to be part of the claimed design.
